UNITED STATES PATENT OFFICE.

FORREST L. SCHOTT, OF CLEVELAND, OHIO.

DESIGN FOR A SUPPORTING BRACKET.

Application filed May 28, 1923. Serial No. 6,302. Term of patent 3½ years.

To all whom it may concern:

Be it known that I, FORREST L. SCHOTT, a citizen of the United States, and resident of Cleveland, county of Cuyahoga, and State of Ohio, have invented a new, original, and ornamental Design for a Supporting Bracket, of which the following is a specification, reference being had to the accompanying drawing, forming part thereof.

In said annexed drawing:—

Fig. 1 is a front elevation of the sup-

porting bracket showing my new design, and Fig. 2 is a side elevation thereof.

I claim:—

The ornamental design for a supporting bracket, as shown.

Signed by me, this 25th day of May, 1923.

FORREST L. SCHOTT.
